Specification for Design.

Patented Dec. 31, 1912.

Application filed April 17, 1912. Serial No. 691,507. Term of patent 7 years.

To all whom it may concern:

Be it known that I, JACOB ROTHLSBERGER, a citizen of the United States of America, and a resident of Muncie, in the county of Delaware and State of Indiana, have invented a new, original, and ornamental Design for Spoons, Forks, or Similar Articles, of which the following is a specification, reference being had to the accompanying drawing, forming part thereof.

Figure 1 is a view of a spoon in full out-

line and a fork in dotted outline, showing my new design. Fig. 2 is a transverse section of the handle of the spoon, fork or similar article.

I claim:

The ornamental design for a spoon, fork, or similar article as shown.

JACOB ROTHLSBERGER.
